DISH CART

Victor D. Molitor, 2829 S. Santa Fe Drive,
Englewood, Colo.

Filed Feb. 27, 1961, Ser. No. 64,084

Term of patent 14 years

(Cl. D14—3)

FIG. 1.

FIG. 2.

FIG. 3.

FIG. 1 is a three quarter front perspective view of a dish cart embodying my new design;

FIG. 2 is a front elevation of the dish cart of FIG. 1; and

FIG. 3 is an end elevation thereof.

I claim:

The ornamental design for a dish cart, as shown.
